United States Patent Office.

WILLIAM F. COLLIER AND JONAH H. BIGELOW, OF WORCESTER, MASSACHUSETTS.

Letters Patent No. 76,032, dated March 24, 1868.

IMPROVEMENT IN BROILERS AND TOASTERS.

The Schedule referred to in these Letters Patent and making part of the same.

TO ALL WHOM IT MAY CONCERN:

Be it known that we, WILLIAM F. COLLIER and JONAH H. BIGELOW, of the city and county of Worcester, State of Massachusetts, have invented certain new and useful Improvements in the Manufacture of Broilers or Toasters; and we do hereby declare the following to be a full, clear, and exact description of the same, due reference being had to the accompanying drawings, and to the letters of reference marked thereon. In said drawings—

Figure 1 shows a perspective view.

Figure 2 shows the manner of holding the slats or wires from slipping.

Figure 3 shows some variations of the same.

The use of wire broilers having become so general, and their peculiar exposure to the heat and gas of the fire, and the vapors of their contents, rendering them so liable to destruction, any device that improves their construction or cheapens their production becomes in the aggregate of much importance.

Our invention relates to both these objects, and consists in forming, in the manner hereinafter described, protuberances on the frame, to hold the cross-bars or wires from slipping on them.

A A (see drawings) is the frame or outside; B B, the bars or slats; C, the handles. On the frame A, we make the projections D D, fig. 2, by punching or pressing on each side, so as to throw out a part of the metal without bending the axis or centre line of the wire forming the frame, as shown at A' in section, through the line a b, and, between D D, we bend the ends of the cross-bars B round A, which keeps them in place. The other parts may be of any of the usual forms. Fig. 3 shows some variations in the manner of making the projections, which in some cases may be desirable, though we consider that shown in fig. 2 the best.

Having described our invention, and the manner in which the same is or may be carried into effect, what we claim, and desire to secure by Letters Patent, is—

The wire frame A A, when provided with a series of ears or projections, D D, formed by pressing out part of the metal without bending the wire, in combination with the bars B B and handles, substantially as and for the purposes herein shown and described.
